DRAWER GUIDE

Charles A. Lindberg and Robert W. Skinner,
Rockford, Ill.; C. Edward Lindberg, executor
of said Charles A. Lindberg, deceased

Application July 28, 1941, Serial No. 404,342

5 Claims.

(Cl. 45—77)

This invention relates to a new and improved drawer guide especially designed and adapted for use on drum type tables but suitable for use in connection with the drawers in home and office furniture generally.

In most furniture no provision is ordinarily made to compensate for shrinking or swelling of the wood under different atmospheric conditions and as a result drawers stick or work hard. It is, therefore, the principal object of our invention to provide a drawer guide constructed to avoid this difficulty and enable easy operation of the drawers at all times regardless of difference in atmospheric conditions.

A salient feature of the drawer guide of our invention consists in the provision of a sheet metal slide plate attached to the guide strip that is fastened to the bottom of the drawer and works in the longitudinal T-slot in the stationary guide in the bottom of the drawer compartment, said plate having opposed longitudinal edge portions for sliding engagement in the cross-portion of the T-slot for non-tilting support of the drawer and also having resilient spring tongue portions on the opposed longitudinal edge portions thereof to work in the cross-portion of the T-slot, so as to maintain light frictional drag which while not enough to interfere with easy operation of the drawer is nevertheless sufficient to steady the drawer so that it does not move too freely and have a feeling of fitting too loosely in its compartment, the thought being to permit manufacture within wide tolerances for absolute freedom from the problem of sticking while nevertheless giving a fine drawer action obtainable heretofore only in high quality furniture made carefully to close tolerances.

The invention is illustrated in the accompanying drawing, in which—

Figs. 1 and 2 are two views of the upper portion of a drum type table, the drawer of which is especially constructed in accordance with our invention and equipped with the novel drawer guide of our invention;

Figs. 3 and 4 are a longitudinal section and transverse section through the drawer guide on a larger scale;

Fig. 5 is a horizontal section on the line 5—5 of Fig. 3, showing the slide plate in plan view, and

Fig. 6 is a section similar to Fig. 4 but showing a modified or alternative construction.

Similar reference numerals are applied to corresponding parts throughout the views.

Referring first to Figs. 1 and 2, 1 designates

the top of a drum type table and 8 is a drawer for the compartment 9 therebeneath. The compartment has a circular bottom 10 and a substantially semi-circular side wall 11. The drawer 8 has a circular bottom 12 and a substantially semi-circular front wall 13 struck on the same radius as the side wall 11, whereby when the drawer is closed there is visible only the two diametrically opposed parting lines 14, where the ends of the front wall 13 meet the ends of the side wall 11, the drawer, in other words, giving the appearance that its front wall forms a rigid part of the lower portion of the table top. The back wall 15 of the drawer is struck on a smaller radius than the front wall 13 and is substantially semi-circular, and is adapted to come into engagement with the inner side of the wall 11 of the table when the drawer is closed, as shown in Fig. 2. This novel construction of the drawer, giving much more commodious and truly useful drawer space, is made feasible only by the drawer guide indicated generally by the reference numeral 16, the guide strip 17 of which is attached to the under side of the bottom 12 and extends substantially diametrically from front to rear relative to the drawer. When the drawer is closed, it can be opened easily by grasping the lower edge portion 18 of the drawer front 13, which, as indicated in Fig. 2, projects downwardly below the bottom wall 10 of the table top structure to the same extent as the side wall 11. In that way there is no need for a drawer pull or knob, although, of course, one or more may be provided if desired.

35 The drawer guide 16 comprises, in addition to the guide strip 17, a T-slot 19 in the bottom 10 of the table top structure and a slide plate 20 fastened to the bottom of the strip 17 and working in the slot. The strip 17 is preferably of wood, and the same is true of the bottom 10 in which the slot 19 is provided. If desired, separate wooden guide strips 21 may be provided, where, for example, the bottom 10a of the table top structure is too thin to permit provision of the T-slot therein. These strips can be fastened by means of screws, as indicated at 22, or in any other suitable way to the bottom 10a so as to define a T-slot 19a therebetween above the bottom 10a. The strip 17 in either case works with a fairly loose fit in the narrower portion 23 of the T-slot, and the slide plate 20 works in the wider portion 24. The plate 20 is of generally rectangular form and is fastened by means of screws 25 to the bottom of the strip 17, the screws being arranged in spaced relation along the longitudinal center line of the

plate and being entered in the strip 17 on its longitudinal center line. The plate is cut away longitudinally on both sides of the center line, as indicated at 26, so as to define a relatively wide middle portion 27 and two relatively narrow spring tongue portions 28 and 29 on opposite sides thereof. The middle portion 27 is wider than the strip 17 and the narrow portion 23 of the T-slot, whereby to provide projecting longitudinal flange portions 30 and 31 on opposite sides of the strip for sliding guiding engagement in the wider portion 24 of the T-slot, in addition to the sliding guiding engagement afforded by the full width butt portion 32 of the plate. In other words, the plate 20 has engagement throughout the full length thereof in the wide portion 24 of the slot 19, so that unit bearing pressure is low under all conditions and the drawer can be opened and closed easily. The spring tongues 28 and 29 are bent longitudinally to generally V-form, so as to provide elbow portions 33 intermediate the ends thereof for sliding engagement with the bottom surface and free end portions 34 for sliding engagement with the top surface in the wider portion 24 of the T-slot. The spring tongue portions 28 and 29 of the plate 20 are flattened out to some extent by entry in the slot 19, so that there is a predetermined pressure exerted at the points 33 and 34 of sliding bearing contact, and it will be noticed that the free end portions 34 of the spring tongues are curved, as indicated in Fig. 3, to facilitate entering the same in the slot when the drawer has been removed and is being replaced. The spring tongues 28 and 29 are shown in leading relation to the butt portion 32 of the plate, but if desired the plate may be reversed end for end in relation to the slide 17. In other words, these tongues may extend rearwardly or forwardly with respect to the drawer and happen to be shown extending rearwardly. The spring tongues 28 and 29, it will be noticed further, are of tapered form narrowing toward the free end portions 34. In that way the tongues are assured of having the desired stiffness and also strength. When the plate 20 is punched from spring steel stock and after forming is properly tempered, the spring tongues will give the desired spring action for the life of the piece of furniture.

In operation, it should be clear that there are no wooden parts in this drawer guide which, by reason of change in atmospheric conditions, can possibly cause the drawer to stick or work hard. The metal plate 20 has sufficient yield in its spring tongue portions 28 and 29 to compensate for any shrinking or swelling that may occur. The spring tongues 28 and 29 serve to keep the middle portion 27 of the slide plate in full engagement with the cooperating surfaces in the slot under substantially uniform pressure at all times, so that the drawer will not be too loose nor too tight but will always be slideable freely. The friction drag is enough to give the drawer a proper feel and action even though the same may be made with greater clearances than the usual practice dictates, the object being to obtain the fine drawer action usually found only in costlier higher grade furniture, where great care has been exercised in the selection of materials and in the making and fitting of the drawer to work easily without much clearance.

It is believed the foregoing description conveys a good understanding of the objects and advantages of our invention. The appended claims have been drawn to cover all legitimate modifications and adaptations.

We claim:

1. As an article of manufacture, a drawer guide slide plate adapted for use in a guide slot of T-shaped cross-section in a guide member, comprising a generally rectangular body portion adapted to be secured along its longitudinal center line to a guide member for sliding engagement in the wider portion of the aforesaid T-shaped guide slot in the cooperating guide member, said plate being formed on opposite sides of the longitudinal center line so as to provide longitudinally extending bowed spring tongues projecting out of and back into the plane of the body of the plate, whereby to provide a bowed portion intermediate the ends of each of said tongues for smooth sliding engagement with a surface in the slot in which said plate operates, and a supporting end portion on the free end of each tongue for slideable supporting engagement of the end of the tongue on another surface in the slot in spaced parallel relation to the first surface.
2. As an article of manufacture, a drawer guide slide plate adapted for use in a guide slot of T-shaped cross-section in a guide member, comprising a generally rectangular body portion adapted to be secured along its longitudinal center line to a guide member for sliding engagement in the wider portion of the aforesaid T-shaped guide slot in the cooperating guide member, said plate being formed on opposite sides of the longitudinal center line so as to provide longitudinally extending bowed spring tongues projecting out of and back into the plane of the body of the plate, whereby to provide a bowed portion intermediate the ends of each of said tongues for smooth sliding engagement with a surface in the slot in which said plate operates, and a supporting end portion on the free end of each tongue for slideable supporting engagement of the end of the tongue on another surface in the slot in spaced parallel relation to the first surface.
3. In an article of furniture constructed of wood and having a drawer compartment and a drawer in said compartment, the relative sizes of the compartment and drawer leaving clearances between the two for an easy working fit, a drawer guide comprising coacting wooden and metal means between the drawer and the bottom wall of the compartment for guiding the drawer in its movement to open or closed position and to support the drawer substantially in its normal plane when extended, said means comprising a wooden guide defining a guide slot of T-shaped cross-section in the bottom of said compartment, a wooden guide strip fitting loosely in the narrow portion of the slot for free reciprocation relative to the compartment bottom and secured to the drawer bottom, and a metal slide plate fastened at the rear end of the guide strip on the bottom thereof and slideable freely in the wider portion of the T-slot, said plate having its opposed longitudinal edge portions formed so as to provide longitudinally extending bowed spring tongues projecting out of and back into the plane of the body of the plate, whereby to provide a bowed portion intermediate the ends of each of said tongues for smooth sliding engagement with the bottom surface in the wider portion of the slot, and a supporting end portion on the free end of each tongue for slideable supporting engagement of the end portion of the tongue on

the upper surface in the wider portion of the slot.

4. In an article of furniture constructed of wood and having a drawer compartment and a drawer in said compartment, the relative sizes of the compartment and drawer leaving clearances between the two for an easy working fit, a drawer guide comprising coacting wooden and metal means between the drawer and the bottom wall of the compartment for guiding the drawer in its movement to open or closed position and to support the drawer substantially in its normal plane when extended, said means comprising a wooden guide defining a guide slot of T-shaped cross-section in the bottom of said compartment, a wooden guide strip fitting loosely in the narrow portion of the slot for free reciprocation relative to the compartment bottom and secured to the drawer bottom, and a metal slide plate fastened at the rear end of the guide strip on the bottom thereof and slidable freely in the wider portion of the T-slot, said plate having its opposed longitudinal edge portions formed so as to provide longitudinally extending bowed spring tongues projecting out of and back into the plane of the body of the plate, whereby to provide a bowed portion intermediate the ends of each of said tongues for smooth sliding engagement with the bottom surface in the wider portion of the slot, and a supporting end portion on the free end of each tongue for slidable supporting engagement of the end portion of the tongue on the upper surface in the wider portion of the slot, that portion of the plate between the tongues being of greater width than the narrower portion of the T-shaped slot for abutment of the mar-

ginal edge portions of the plate next to the tongues with the upper surface in the wider portion of the slot.

5. In an article of furniture constructed of wood and having a drawer compartment and a drawer in said compartment, the relative sizes of the compartment and drawer leaving clearances between the two for an easy working fit, a drawer guide comprising coacting wooden and metal means between the drawer and the bottom wall of the compartment for guiding the drawer in its movement to open or closed position and to support the drawer substantially in its normal plane when extended, said means comprising a wooden guide defining a guide slot of T-shaped cross-section in the bottom of said compartment, a wooden guide strip fitting loosely in the narrow portion of the slot for free reciprocation relative to the compartment bottom with freedom for limited lateral and vertical movement and secured to the drawer bottom, and a metal slide plate fastened at the rear end of the guide strip on the bottom thereof and slidable freely in the wider portion of the T-slot with freedom for limited lateral movement and spring restrained vertical movement, said plate having at least one bowed spring tongue thereon projecting from the plane of the plate for sliding engagement at its intermediate elbow portion on the lower surface of the wider portion of the T-slot and at its free end portion on the top surface of the wider portion of the T-slot, so as to hold the plate resiliently in engagement with the upper surface in the wider portion of the T-slot.
